UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,224,968.

Specification of Letters Patent.

Patented May 8, 1917.

Application filed December 11, 1916. Serial No. 136,240.

To all whom it may concern:

Be it known that I, GEORGE A. SEIB, citizen of the United States, and resident of Ilion, in the county of Herkimer and State 5 of New York, have invented certain new and useful Improvements in Type-Writing Machines, of which the following is a specification.

My invention relates to typewriting machines and it has for its object to provide improved dead key mechanism for such machines. Specifically stated, the principal object of the invention is to provide, in a case shift typewriter, means whereby one of 10 the types on a type bar can print an accent mark, for example, which requires no letter space, and the other type on the same type bar can print a character that does require letter spacing, and that the escapement will 15 be operated in one case position and not in the other, the ribbon vibrator, if present, being operated in both instances.

One form of my invention is illustrated in the accompanying drawings, in which—

20 Figure 1 is a partial front to rear section of a typewriting machine having my invention embodied therein.

Fig. 2 is a fragmentary enlarged view of a portion of the same but with the ribbon 25 mechanism in operated position.

Fig. 3 is a rear elevation in section about on the line $x-x$ of Fig. 1.

Fig. 4 is a fragmentary plan view of that 30 portion of the mechanism which is in the base of the machine.

I have shown my invention embodied in a machine which in most respects is like the No. 10 Remington typewriter. The main frame of this machine comprises a base 1 from which rise posts 2 which support a top plate 3, and on said top plate there is a carriage, of which I have shown in the drawing on the roller platen 4 and feed rack 5. Said feed rack meshes with a feed pinion 6 35 on the front end of a shaft, which at its rear end carries an escapement wheel 7, said shaft being journaled in a housing 8 mounted on the top plate 3. The escapement wheel 7 is controlled by feed dogs 10 mounted on a dog rocker 11 suitably pivoted in the stationary framework and having an arm 12, which is connected by a link 13 with an arm 14 mounted on a rock shaft 15, which is pivoted at its ends on pivot screws

16 secured to the side bars of the base 1. 55 Said rock shaft 15 has arms 17 projecting rearward therefrom, Fig. 4, and, by means of links 18, supporting a universal bar 20. Said universal bar lies beneath the printing key levers of the machine, four of which are 60 partially shown in the drawings, three of these being special key levers 21 and the fourth an ordinary key lever 21^a. The rock shaft 15, being thus connected to the universal bar, is operated by all of the ordinary 65 printing keys and it may, therefore, be termed a universal member. The key levers 21 are pivoted to a slotted plate 22 and are provided with returning springs 23. I have not deemed it necessary to show these key 70 levers in full because they are a part of the well-known Remington machine.

In that machine each of said key levers has a depending lug consisting of a vertical screw 24 that is situated over the universal 75 bar 20 and by means of which said key levers when operated depress the said universal bar.

The key levers 21 operate type bars 25 having two types 26 and 26^a thereon, which 80 bars when one of the keys is operated are adapted to strike against the front face of the platen 4. In the normal position of the parts the lower one 26 of the two types strikes the platen and this is therefore the 85 lower case type, and when the platen is shifted upward the upper case type 26^a strikes the platen. The case shift mechanism of the Remington machine comprises a shift rail 27, Fig. 1, on which runs a roller 90 or wheel mounted on the shiftable platen frame of the machine, and said rail 27 can be shifted up and down by means not herein fully shown, but which is shown in my prior Patent No. 1,203,795, dated November 7, 95 1916. Said rail is carried by two irregularly-shaped arms or brackets 28, and each of said arms or brackets is at its lower end pivoted at 30 to the rear arm of a lever 31. Said levers are pivoted on a cross rod 32, each of them extending to the keyboard of the machine where it is provided with a case shift key 33; and the two levers 31 are connected by a heavy transverse bar 34 to cause them to rock in unison.

100 The ribbon vibrator mechanism can be, as to part of its construction, of any suitable sort, such, for example, as that shown in my

105

prior patent above referred to; but for the sake of simplicity I have here shown more or less conventionally a vibrator 35 having its stem 36 pivoted to the forwardly directed 5 arm of a bell crank 37, which bell crank is pivoted at 38 to a bracket 40 secured to the shift rail 27. Said bracket has an upwardly and forwardly extending arm terminating in a guide 41 for the vibrator. The depending arm of the bell crank 37 is connected by a link 42 with the upper end of a lever 43 of the first order, which is pivoted at 44 to lugs 45 projecting from the stationary part of the machine, these lugs in the No. 10 Remington projecting from the type bar segment 45^a. In Fig. 3 the lever 43 is shown as a built-up frame comprising two lever arms spaced apart and connected at their lower ends by a cross rod 46, this being the form 20 of lever employed in the ribbon mechanism set forth in my said prior patent. In said patent the link 42, bell crank 37 and bracket 40 are replaced by a more complicated mechanism adapted to provide for the use 25 of a bi-color ribbon and for throwing the ribbon out of operation for mimeographing; and some such complete ribbon mechanism is preferably employed, although the simpler form shown in this application can also 30 be employed.

The rod 46 passes through an open-ended slot 47 in a lever 48, which is pivoted on a pivot screw 49 to the side of the arm 14. The lever 48 has a rearwardly directed arm 35 from which an ear 50 is bent off beneath the arm 14 and through said arm 14 is screwed an adjusting screw 51 having a lock-nut 52. The lower end of said screw 51 is adapted to contact with the ear 50 in 40 such fashion that when the shaft 15 is rocked the arm 14 is thereby moved downward and the lever 48 partakes of the motion of said arm 14 and moves the rod 46 toward the rear of the machine, thus moving the upper end 45 of the lever 43 toward the front of the machine and operating the vibrator. The lever 48 can be operated independently of the arm 14, however; said lever in such case turning about its pivot 49 and being restored to its normal relation to said arm 14 by means of a spring 53; the construction in 50 this respect being like that shown in my prior patent and at present employed in the No. 10 Remington machine.

55 In order to operate the lever 48 and the ribbon mechanism independently of the arm 14 and the escapement mechanism, said lever 48 is connected by means of a link 54 with a secondary universal bar 55 supported 60 at its ends by arms 56 which are pivoted on the cross rod 32. The link 54 is connected with said universal bar by means of a pin 57 passing through a slot 58 in a bracket 60 secured to the universal bar 55 near the 65 middle of the machine. The construction is

such that if said universal bar 55 be depressed the lever 48 will be operated; but if said lever be operated by the universal bar 20 acting through the arm 14, the link 54 can move downward without disturbing the universal bar 55. Said universal bar 55 is provided with returning springs 61 and with stops 62 which limit its upward motion by contact with the base-frame. 70

In case it is desired to make any key a 75 dead key the screw 24 of that key lever is either removed entirely or is screwed up so high that it will not operate the universal bar 20, and underneath that same key lever another screw 63 is screwed up through the 80 universal bar 55 into such position that a depression of said key lever will, through said screw, operate said universal bar 55 and will thus operate the ribbon vibrator but not the escapement. The arrangement 85 just described is that at present employed in the Remington machine.

In order to provide for making any desired printing key a live key in lower case and a dead key in upper case, or vice versa, 90 I remove entirely from that key lever the screw 24 and place beneath said key lever one of the screws 63; and I provide means for connecting that key lever with the rock shaft 15 in one position of the case shift 95 mechanism and for disconnecting said key lever from said rock shaft in the other position of said mechanism. To this end I replace the screw 24 with a screw 64 having a wide flat head 65 and I pivot to the upper 100 side of the rock shaft 15 a coupler, here shown as an arm or plate 66 adapted to be turned in under the head 65 of the screw or to be turned to another position away from said screw head. Said plate or arm 66 has 105 a hub 67 through which passes a pivot screw 68 screwed into the shaft 15 so as to allow the arm 66 to be turned in right and left-hand directions, but so that in case said arm is depressed by the head 65 the shaft 15 will 110 be rocked to actuate the ribbon vibrator and the escapement in the same general manner that it is rocked by the universal bar 20 when depressed by an ordinary printing key lever. If the arm 66 is not in register with 115 the screw head 65 then a depression of the key lever carrying the screw head will fail to rock the shaft 15 and the escapement will remain at rest. But at this stroke the ribbon vibrator will be actuated through the 120 screw 63, secondary universal bar 55, link 54, lever 48 and frame 43.

The arm 66 can be connected with the case shift mechanism in various ways, the means here shown consisting of a wire 70 passing 125 through a hole in the arm 66 and at its upper end secured to a rightangled bracket 71 secured, as by screws 72, to one of the shift brackets 28. In the present instance the wire is shown threaded and provided 130

with two nuts 73, one on each side of the bracket 71. The wire 70 is bent near its lower end as shown at 70^a in Fig. 3 so that when the platen is in lower case position the 5 part of the wire that projects beneath the plate 66 is inclined toward the right and when the shift key is operated and the bracket 28 is moved upward this wire is drawn through the plate 66 and cams said 10 plate toward the right. While in the present instance the wire is bent at its lower end toward the operator's right so that when the case shift key is depressed the plate 66 will be swung toward the operator's right it will 15 be understood that said wire may be bent toward the left to swing the plate toward the left, if desired. As herein shown, this particular plate 66 is at the extreme left-hand side of the machine and in the lower case 20 position of the platen it extends straight toward the rear of the machine with its rear free end lying beneath the head 65 of the screw 64. In this position of the plate its associated key 21 is a live key, but if the 25 case shift key be depressed this plate will be swung off to the observer's left and will be swung out from under the screw head and in that position of the parts this will be a dead key and at that time the escapement 30 will not be operated. The type bar that is operated by this key will have an accent mark on it for printing in the upper case position and some other character that requires letter spacing for lower case 35 position.

In case it is desired to have several of these keys a screw 64 and a coupler 66 are provided for each such key, and the several couplers can all be operated by one wire 70. 40 In the present instance, I have shown associated with three keys three of the coupler plates 66 all connected together by a link or bar 74 pivoted to each of said plates as by a pivot screw 75. The construction is such 45 that when one of said plates is swung toward the right or toward the left by the shift mechanism the remaining plates will also be swung in the same direction.

It will be understood that any key 50 equipped in this way can be made either normally live or normally dead. In Fig. 4 I have shown two keys near the right-hand side of the figure arranged to be normally live keys and to be dead keys in the upper 55 case position; and I have also shown another key near the middle of the machine which is a dead key in the lower case position and a live key in the upper case position. The last mentioned key lever has its 60 plate 66 normally inclined toward the observer's right and out of the path of the screw head 65. If the case shift key be operated and all of the plates 66 be swung toward the left in Fig. 4 the two said plates at 65 the right-hand side of the figure will be

moved into inoperative position and the one near the middle of the figure will be moved to operative position. The arrangement can be varied at convenience.

It will also be understood that in the same machine there can be one or more keys that are dead in both case shift positions. Such a key lever would not be provided with any plate 66 but would be made a dead key in the same manner as heretofore, namely, by withdrawing the screw 24 and placing beneath said key lever one of the screws 63.

In the operation of the machine the action of the ordinary keys will be as usual heretofore. The two special key levers 80 shown at the right-hand side of Fig. 4 are connected to type bars, each of which has a lower case type 26 adapted to print some ordinary character, such as a numeral, and an upper case type 26^a adapted to print some character, such as an accent, that does not require letter spacing; and when either of these keys is operated, the case shift mechanism being in normal position, the lower case character will be printed, the universal 85 bar 55 will be depressed, and the rocker 15 will be operated by means of one of the couplers 66, which coupler will be depressed by the screw head 65; and the operation of said rocker will work the escapement to feed the 90 carriage. When one of the upper case or accent types is used the shifting upward of the frame 28 and with it the wire or cam 70 will shift the coupler 66 toward the observer's left in Fig. 4 out from under the 95 screw head 65. The depression of the printing key will then result in printing the accent and in an operation of the ribbon vibrator through the instrumentality of the special universal bar 55, but the rocker 15 100 and the escapement mechanism will not be operated.

It will be understood that that special key lever 21 shown to the left of the middle of Fig. 4 is connected with a type bar whose 110 lower case type 26 is an accent or other mark that does not require letter spacing and whose upper case type 26^a prints some character that does require letter spacing. If this key lever be depressed when the case 115 shift mechanism is in normal position the universal bar 55 and the ribbon vibrator will be operated, but the escapement will not be operated, the coupler 66 being out of register with the screw head 65; but if the 120 platen be moved to upper case position this coupler will be swung to the left underneath said screw head and a depression of this key at that time will result not only in an operation of the ribbon vibrator but also 125 in an operation of the rocker 15 and of the escapement mechanism.

Various changes can be made in the details of construction and arrangement without departing from my invention.

What I claim as new and desire to secure by Letters Patent, is:—

1. In a typewriting machine, the combination of a series of printing keys, a universal member operated by said keys, a special key, and a coupler movably mounted on said universal member and capable of being moved into and out of position to couple said special key to said universal member.
2. In a typewriting machine, the combination with a carriage and carriage feed mechanism including a universal member, of a series of printing keys, each adapted to operate said universal member at each stroke of said keys, a special printing key, and a coupler mounted on said universal member and movable into and out of position operatively to connect said special key with said universal member.
3. In a typewriting machine, the combination with a carriage and carriage feed mechanism including a universal member, of a series of printing keys each adapted at each stroke thereof to operate said universal member, a special key, and an arm adjustably mounted on said universal member and movable into and out of position operatively to connect said special key with said universal member.
4. In a typewriting machine, the combination with a carriage, carriage feed mechanism including a universal member, and case shift mechanism, of a series of keys each adapted to operate said universal member, a special key, a coupler mounted on said universal member and movable into and out of position to connect said special key with said universal member, and means whereby said case shift mechanism controls said coupler.
5. In a typewriting machine, the combination with a carriage, carriage feed mechanism including a universal rock shaft, and case shift mechanism, of a series of keys each adapted to operate said rock shaft, a special key, and a coupler mounted on said rocker and movable by said case shift mechanism into and out of position to connect said special key with said rock shaft.
6. In a typewriting machine, the combination with a carriage, carriage feed mechanism including a universal member, and case shift mechanism, of a series of printing keys each adapted to operate said universal member, a special printing key, an arm pivoted on said universal member, and means whereby said case shift mechanism swings said arm about its pivot into and out of position to connect said special key with said universal member.
7. In a typewriting machine, the combination with a carriage, carriage feed mechanism including a universal member, and case shift mechanism, of a series of printing keys each adapted to operate said universal member, a special printing key, an arm pivoted on said universal member and movable into and out of position to connect said special key with said universal member.
8. In a typewriting machine, the combination with a carriage, a carriage escapement, a ribbon vibrator and case shift mechanism, of a universal member connected to operate both said escapement and said ribbon vibrator, a universal bar connected to operate said vibrator but not said escapement, a series of printing keys arranged to operate said universal member, one or more special printing keys arranged to operate said universal bar, and one or more couplers for said special key or keys, said coupler or couplers being pivoted to said universal member and connected to be shifted by the said case shift mechanism into and out of position operatively to connect said special key or keys with said universal member.
9. In a typewriting machine, the combination with a carriage, carriage feed mechanism, and case shift mechanism, of a series of printing keys, a universal bar lying beneath said keys, means whereby said keys operate said universal bar, one or more special printing keys arranged so as not to contact with said universal bar, and special couplers above said special keys, said couplers operatively connected with the universal bar and movable by said case shift mechanism into and out of position to connect said universal bar with said special keys.
10. In a typewriting machine, the combination of a series of printing keys, a rock shaft above said keys, a universal bar beneath said keys and connected with said rock shaft, one or more special printing keys and one or more couplers mounted on said rock shaft and movable into and out of position to connect said special key or keys with said rock shaft.
11. In a typewriting machine, the combination with a carriage, carriage escapement, a ribbon vibrator, and case shift mechanism, of a series of printing keys including ordinary keys and special keys, an ordinary universal bar arranged to be operated by said ordinary keys and connected with said escapement and with said ribbon vibrator, a special universal bar connected with said vibrator but not with said escapement, and said special universal bar being arranged to be operated by said special key or keys; and one or more coupling devices controlled by said case shift mechanism to couple said special key or keys to and uncouple them from said ordinary universal bar.
12. In a typewriting machine, the combination with a series of printing keys each having a lug thereon, a universal bar adapt-

- ed to be operated by said lugs, one or more special printing keys devoid of said lug but having another abutment differently disposed so as not to operate said universal bar, and one or more couplers for said special key or keys, said couplers connected with said universal bar and movable into and out of coöperative relation to said other abutment or abutments.
- 10 13. In a typewriting machine, the combination with printing keys 21^a, universal bar 20, and universal member 15, of a special key having an abutment 65, and a coupler 66 mounted on said member 15 and movable into and out of coöperative relation to said abutment 65, substantially as shown and described.
- 15 14. In combination with a case-shifting means, the printing keys and the types, of a universal member, a plurality of couplers for the keys mounted on said member and operative simultaneously by the case-shifting means.
- 20 15. In combination with a case shifting means, the types and the printing keys provided with abutments, of a universal member, a plurality of couplers adapted to actu-
- ate said member and also adapted to be moved into and out of engaging position with said abutments, and means whereby 30 all of said couplers are operative simultaneously by the case shifting means.
- 25 16. In a typewriting machine, the combination with a universal member 15 of a plurality of special keys, a plurality of couplers 35 66 mounted on said member 15, and movable into and out of position to be operated by said keys, and means including a link 74 to move said couplers together.
- 30 17. In a typewriting machine, the combination with case shift mechanism and a universal member 15, of a special key, a coupler 66, and a cam 70, said cam mounted on a part of said case shift mechanism and acting to move said coupler into position to 40 connect said special key with said universal member.

Signed at Ilion, in the county of Herkimer and State of New York, this 6th day of December, A. D. 1916.

GEORGE A. SEIB.
